(57) **CLAIM**

The ornamental design for an electrician's centerline template, as shown and described.

DESCRIPTION

FIG. 1 is a top plan view of an electrician's centerline template incorporating my new design;

FIG. 2 is a side elevational view thereof, the other side elevational view being the same as that shown;

FIG. 3 is a bottom plan view thereof; and,

FIG. 4 is an end elevational view thereof, the other end elevational view being the same as that shown.
